C. E. HOCKING

EXPANSION REAMER

Filed Oct. 11, 1924

FIG. 1.

FIG. 2.

FIG. 4.

FIG. 3.

Inventor
Charles E Hocking

By Roland J. Whitaker

his Attorney

UNITED STATES PATENT OFFICE.

CHARLES E. HOCKING, OF LANCASTER, PENNSYLVANIA.

EXPANSION REAMER.

Application filed October 11, 1924. Serial No. 743,154.

To all whom it may concern:

Be it known that I, CHARLES E. HOCKING, a citizen of the United States, and a resident of Lancaster, in the county of Lancaster 5 and the State of Pennsylvania, have invented a new and useful Improvement in Expansion Reamers, of which the following is a specification.

My invention relates to expansion reamers 10 and its principal object is the provision of a ring or collar to hold the blades securely in place.

Another object of my invention is to produce a steady or follower ring to fit on the 15 shank to hold the bevelled ends of the cutters, to give the cutters additional support or strength and to prevent chattering of the cutters or blades.

Other objects and advantages of the invention will appear during the course of the following description taken in connection with the drawing.

Figure 1 is an elevation of the expansion reamer.

Fig. 2 is a longitudinal view partly in section.

Fig. 3 is a transverse sectional view of the reamer taken on line 3—3 of Fig. 1, and

Fig. 4 is a perspective view of the steady 30 ring.

Referring to the drawing in detail, wherein similar characters of reference designate similar parts throughout the several views, the numeral 5 designates a shank having the 35 usual squared end. Running longitudinally of the shank 5 are a plurality of grooves 6 inclined as clearly illustrated in Fig. 2.

In the reamer head or cutting area 7 are blades or cutters 8. Each is preferably of 40 semi-high speed tool steel and tapered to fit into an inclined groove 6. The blades 8 are also tapered at each end as shown at 9. Adjusting nuts 10 are threaded to the shank 5.

Instead of the usual bevelled locking ring, I have devised a steady or follower ring 11. The base edge of each ring or collar 11 is flat while the opposite edge has spaced notches 12 having bevelled faces 13 to coact with 45 tapered faces 9.

Not only do the notches or slots 12 give the ring 11 a castellated appearance, but it will be noticed that the inside diameter varies, that is—it tapers.

In operation, the blades 8 fit into the 55 grooves 6 and the steady ring or collar 11 is turned so that each notch or slot 12 engages end 9 of the blade 8. The adjusting nut 10 is then tightened against the base edge of the steady ring. 60

The purposes of the steady ring 11 should be apparent. It will support and protect the ends 9 of blades 8. All the blades 8 are united into one supporting unit. The collar 11 and the end of each blade 8 is given 65 the combined strength of the numerous blades. As the steady ring firmly holds the blades in cutting position, the adjusting nuts will not spin or break and furthermore the ring with its slots will prevent the blades 70 from becoming loose and prevent the chattering of the blades. The notches firmly secure each blade against radial movement and end thrust.

It is understood that the form of my invention herein shown and described is to be taken as a preferred example of the same, and that various changes in the shape, size and arrangement of parts may be resorted to without departing from the spirit of the 75 80 invention or the scope of the subjoined claim.

Having thus described my invention, what I claim as new and desire to secure and protect by Letters Patent in the United 85 States is:

An expansion reamer comprising in combination, a spindle, a plurality of longitudinal grooves in said spindle, a plurality of reamer blades longitudinally adjustable in 90 the grooves, adjusting nuts threaded upon the spindle and disposed at opposite ends of the blades and steady rings received on the spindle and interposed between the nuts and blades, said rings being provided with 95 notches in their outer edges adjacent the blades, each notch being beveled in the same plane as an end of a blade so as to receive the same.

CHARLES E. HOCKING.
